UNITED STATES PATENT OFFICE.

JOHN G. WINTJEN, OF MOUNT VERNON, NEW YORK.

DRESS-ELEVATOR.

SPECIFICATION forming part of Letters Patent No. 485,780, dated November 8, 1892.

Application filed February 6, 1892. Serial No. 420,559. (No model.)

To all whom it may concern:

Be it known that I, JOHN G. WINTJEN, a citizen of the United States, and a resident of Mount Vernon, in the county of Westchester 5 and State of New York, have invented certain new and useful Improvements in Dress-Elevators, of which the following is a specification.

This invention relates to an improved dress-elevator which is to be used by ladies for lifting the skirt of the dress in rainy weather, either temporarily or permanently, the skirt being lowered again by its own weight whenever the dress-elevator is released; and the 10 invention consists of a dress-elevator which is attached to the inside of the skirt below the waistband, and which comprises a cord-guide that is attached to the skirt, said cord-guide being composed of an interior spirally-coiled 15 wire and an exterior covering, a dress-lifting cord that is passed through said guide and provided with a ring for pulling the same, and with auxiliary cords having ring-shaped 20 ends that are attached to the dress and connected to the lower end of the lifting-cord. The lower end of the covering of the cord-guide is not attached to the skirt but provided with slits or notches, so that it can 25 yield sufficiently with the cord-guide during 30 the use of the dress-elevating device.

In the accompanying drawings, Figure 1 represents a side elevation, with a part broken away, of my improved dress-elevator, showing it attached to the inside of a skirt. Fig. 35 2 is a front elevation of the skirt, showing the exterior front end of the dress-elevator. Fig. 3 is a perspective view of the dress-elevator, drawn on a larger scale and ready for being attached to the skirt; and Fig. 4 is a detail 40 side view of a portion of the cord-guide of the dress-elevator.

Similar letters of reference indicate corresponding parts.

Referring to the drawings, A represents the 45 skirt of a lady's dress, and D D' the cord-guide, through which the cord E for lifting the dress is passed. The cord-guide D D' is composed of an exterior covering D of leather, japanned cloth, buckram, or other suitable 50 fabric, the overlapping parts of which are cemented together and connected by eyelets, stitches, or otherwise. In the bight at the

lower edge of the covering is inserted an interior spirally-coiled wire D', which extends along the lower part of the covering D and 55 which forms a tubular guide for the lifting-cord. The spirally-coiled wire D' is provided at the upper end with a sleeve D², having an enlarged head that is soldered or otherwise attached to the coil D', so as to prevent the 60 latter from being drawn through the covering by the strain exerted on the same by the weight of the skirt. The skirt-lifting cord E is passed through the coil of the tubular cord-guide D and provided with a ring e at its upper end, said ring having a suitable tassel e' or other device for conveniently taking hold 65 of the same. To the lower end of the skirt-lifting cord E are connected a number of auxiliary cords E' of different lengths that 70 are provided with rings e² at their lower ends, by which said cords are attached to different points at the lower part of the skirt. The knots by which the auxiliary lifting-cords E' are attached to the rings and to the end lifting-cord E are covered by means of braided sleeves e³, by which a neat appearance is imparted to the dress-lifting device. The covering D is stitched to the inside of the skirt at some distance below the waistband, as 75 shown clearly in Fig. 1, the lower part of the cord-guide D D' being not attached to the skirt, so as to yield and adapt themselves to the strain exerted thereon by the dress-lifting cords E E'. For this purpose the covering of the cord-guide D D' is provided with slits or notches f, that extend close to the 80 coiled-wire guide D', as shown in Fig. 3, so that it readily adapts itself to the different curves to which the lower end of the cord-guide is bent. The upper end of the dress-lifting cord E is passed through an opening e⁴ in the skirt to the front part of the same, as shown in Fig. 2, so that the ring and tassel at the end of the same can readily be taken 85 hold of whenever it is desired to lift the skirt. At the front part of the skirt is further arranged a fixed hook g, to which the ring e is applied whenever it is desired to support the dress permanently in lifted position, as in 90 stormy weather or when shopping. For temporarily lifting the dress—as, for instance, when crossing a street—the tassel is simply pulled and the skirt held long enough in

raised position, after which the tassel is released and the skirt returned to its former position by its own weight.

My improved dress-elevator can be cheaply manufactured and readily attached to the skirt of the dress, an opening like a small buttonhole being arranged in the front part of the skirt, so as to receive the headed sleeve at the upper end of the cord-guide, around 10 which the opening is closed by means of stitches. The skirt can be readily lifted whenever necessary by pulling the tassel of the dress-lifting cords, the skirt dropping gracefully when in raised position. Either 15 the temporary or permanent elevation of the dress may be readily secured, as before described, without indicating from the outside of the skirt the extra strain exerted thereon.

Having thus described my invention, I 20 claim as new and desire to secure by Letters Patent—

A dress-elevator composed of a cord-guide

formed of an interior closely-coiled wire, an exterior covering extending over said coiled wire and being united at the overlapping parts, the lower overlapping portion of said covering being slotted or notched, so as to yield to the strain on the same, a headed sleeve attached to the upper end of the wire tube, a dress-lifting cord passing through the 25 interior coiled wire, a ring at the upper end of the lifting-cord, auxiliary dress-lifting cords attached to the lower end of the main lifting-cord, and rings at the lower ends of the auxiliary cords and adapted to be attached to the 30 skirt, substantially as set forth.

In testimony that I claim the foregoing as my invention I have signed my name in presence of two subscribing witnesses.

JOHN G. WINTJEN.
